UNITED STATES PATENT OFFICE.

SIGMUND BERGMANN, OF NEW YORK, N. Y., ASSIGNOR TO BERGMANN & CO., OF SAME PLACE.

SOCKET FOR INCANDESCENT ELECTRIC LAMPS.

SPECIFICATION forming part of Letters Patent No. 311,100, dated January 20, 1885.

Application filed April 10, 1884. (No model.)

To all whom it may concern:

Be it known that I, SIGMUND BERGMANN, of New York, in the county and State of New York, have invented certain new and useful 5 Improvements in Sockets for Electric Lamps, of which the following is a specification.

My invention relates to sockets for use with those incandescent electric lamps whose terminals are a screw-threaded ring and a plate 10 on the base of the lamp, the lamp being screwed into the socket and making contact with corresponding terminals within the same; and my object is to provide a socket of this kind which shall be compact and of as few parts as 15 possible; in which the amount of insulating material used shall be very small, and which shall contain a simple and effective form of circuit-controller. The manner in which I accomplish this object is shown in the accompanying drawings, in which—

Figure 1 is an elevation of the socket complete; Fig. 2, a vertical section of the same; Fig. 3, a bottom view of the insulating-disk, which carries the terminals and circuit-controller; Fig. 4, a top view of the socket, with its exterior metal casing removed; Fig. 5, an elevation of the socket, with the outer casing and contact-sleeve removed, and viewed from the side opposite the key; and Fig. 6, an elevation of the base of the lamp.

Like letters refer to corresponding parts in all these figures.

A is a disk of insulating material. I prefer to use a non-combustible and non-carbonizable material, such as lava. This is desirable in a socket of this character, because the contacts and terminals are placed close together in a small space, so that there may sometimes be danger of a short-circuit between them, and also circuit is continually being made and broken by the socket-key, in some cases causing considerable spark. I would here state that I am aware of United States Patent to Sawyer and Man, No. 45 229,476. The disk has a central aperture, a, and raised walls, b b on each side of said aperture.

Upon the top of the disk A is placed an externally and internally screw-threaded metal sleeve, B, having an inward flange, c, at its lower end, through which screws d d' pass, securing the sleeve to the insulating-disk.

The flange c encircles the central elevation, b b, of the disk. The ring or band terminal B' of the lamp is screwed into the sleeve B, whereby connection is made between these two parts, and the plate or tip terminal of the lamp rests upon the raised part b b of the insulating-disk. The disk A is supported from below by means of the flat metal ring C, from which a part, D, extends up, having horizontal projections e e, to which disk A is secured. The sleeve f for the circuit-controlling key extends inwardly from the part D. The ring or plate C, upwardly-extending part D, and sleeve f are preferably all made in one piece. On the lower side of disk A is also secured by screws the plate g, which has a downwardly-extending part, h, carrying a binding-screw, k, to which one of the circuit-wires is to be attached. The screw d, passing through flange c and disk A, enters the plate g, thus connecting the circuit-wire with the sleeve B, as well as assisting in securing the sleeve to the disk.

E is a metal piece, secured by screws to the under side of disk A. Arm l extends from it, being turned at right angles for compactness, and carries binding-screw k', which is the other circuit-wire terminal. All the screws 80 a' which secure the metal parts below the disk to it have their heads embedded in the disk and covered with an insulating-cement or other material, so that they cannot come in contact with sleeve B. For this reason they 85 are not visible in Fig. 4. The two bent springs m m' are attached by rivets to the piece E. One of these, m, passes through the central aperture in the disk A, and has its end m' bent horizontally, passing through slot or opening n in the lower portion of sleeve B, and resting, when the circuit is open, upon the upper side of disk A. Spring m' is a re-enforcing spring to assist the action of the spring m. Through the sleeve f passes the circuit-controlling key, which is a metal rod, o, having a thumb-piece, F, outside the socket, and an insulating-tip, p, which presses against the spring m. The insulating-tip removes the key from the circuit. The key has a pin, r, which 100 passes through the oblique slot s in sleeve f, so that when the key is turned it presses against spring m and throws its bent end m' up against the plate terminal m' of the lamp,

which, when the lamp is screwed in, rests upon the central elevation, *b b*, which prevents the terminal from touching the flange *c*. The connection formed when the circuit is closed 5 is a reliable spring-contact, and one which allows the lamp to be turned in the socket without breaking connections. To close circuit, the key is turned until pin *r* rests in notch *t*, and to open circuit, the key is turned 10 to back from said notch, when *m m'* spring back, bringing *m²* down upon the disk *A* again. The socket is completely inclosed by a metal 15 casing. The ring or plate *C* is covered by cap *G*, which is held by flat-headed screws *u u*, inserted in ring *C*, whose heads pass through oblong apertures in the cap and are then turned across the apertures. From the lower side of the cap extends an internally-screw-threaded sleeve or tube, *H*, soldered to or made in one 20 piece with the cap. This is screwed upon the fixture through which the circuit-wires run, extending through sleeve *H* into the interior of the socket, where, as before stated, they are held by binding-screws *k k'*. A set-screw, 25 *v*, passes through the side of sleeve *H* and is set against the fixture, to prevent the turning thereon of the socket and consequent twisting of the wires. A metal shell, *I*, is placed over the upper part of the socket setting in the 30 cap *G*, and having a slot for the circuit-controlling key. The portion of the slot below the key is filled by a plate, *y*, secured to part *D* by rivets or screws *z*. Finally, a flanged ring, *K*, of hard rubber or other suitable 35 insulating material, is screwed in between sleeve *B* and shell *I*, serving to keep these parts separate and to hold the shell in place.

The socket, constructed as described, is of a neat appearance, is very compact, has no useless mass of insulating material, being merely a metal skeleton with just enough insulation to separate the terminals, all the circuit-connections being carried by the single insulating-disk instead of being divided among 5 two or more insulating portions, as heretofore. The circuit-controller making and breaking circuit upon the lamp-tip employs fewer parts and is simpler in construction than any heretofore used, while it is very efficient in operation, and the whole may be put together or taken apart with great readiness, the parts being easily separable.

What I claim is—

1. In a socket for an electric lamp, the combination of two circuit terminals, one a sleeve adapted to make contact with the band or ring terminal, the other a spring movable into and out of contact with the bottom terminal of the lamp, substantially as set forth.
2. In a socket for an electric lamp, the combination of a disk of insulating material, a contact-sleeve carried by said disk, for making contact with the band or ring terminal of the lamp, and a contact-piece, also carried by said 5 disk, for making contact with the bottom terminal of the lamp, substantially as set forth.

3. In a socket for an electric lamp, the combination, with a disk of insulating material, of a contact-sleeve for making contact with the band or ring terminal of the lamp, a contact-piece for making contact with the bottom terminal of the lamp, and two terminals for the circuit-wires leading to the socket, all said socket contacts and terminals being carried by the said insulating-disk, substantially 70 as set forth.

4. In a socket for an electric lamp having two terminals for making connection with corresponding lamp terminals, the combination of a metal supporting portion and a disk of 80 insulating material carried thereby and carrying all the terminals and contacts of the socket, substantially as set forth.

5. In a socket for incandescent electric lamps having a bottom terminal movable into 85 and out of contact with the plate terminal of the lamp, the insulating-disk having a raised portion meeting said plate terminal, substantially as set forth.

6. The combination of the insulating-disk 90 having an aperture in its center, and the contact-spring working through such aperture, for making and breaking circuit with a lamp terminal, substantially as set forth.

7. The combination, with the insulating-disk having a central aperture, of a contact-spring secured beneath said disk, passing through the aperture, and bent horizontally above the disk, substantially as set forth.

8. The combination of the sleeve *B* and the 100 movable contact-spring *m'*, said sleeve having a slot to allow the movement of said spring, substantially as set forth.

9. The combination, with a contact-spring, substantially of the form described, of a separate 105 turning-key bearing against said spring, whereby it may be forced upward to make contact, substantially as set forth.

10. The combination of the sleeve *B*, the insulating-disk, and a circuit-wire terminal 110 beneath said disk, with the connecting-screw extending through the disk from said sleeve to said terminal, substantially as set forth.

11. The combination, with the insulating-disk and metal parts attached thereto, of the 115 attaching-screws having their heads covered with insulating material, substantially as set forth.

12. The combination of the circuit-closing spring and the metal key for moving the same, 120 said key having an insulating-tip, substantially as set forth.

13. In a socket for electric lamps, the insulating-body which supports the terminals or connections, formed of non-combustible material, substantially as set forth.

This specification signed and witnessed this 4th day of April, 1884.

SIGMUND BERGMANN.

Witnesses:

WM. H. MEADOWCROFT,
T. G. GREENE, Jr.

It is hereby certified that in Letters Patent No. 311,100, granted January 20, 1885, upon the application of Sigmund Bergmann, of New York, New York, for an improvement in "Sockets for Incandescent Electric Lamps," an error appears requiring the following correction, viz: The grant should read that the said patent was assigned to *Bergmann and Company, its successors or assigns*, instead of "Bergmann & Co., their heirs or assigns;" and that the grant should be read with this correction therein to make it conform to the records pertaining to the case in the Patent Office.

Signed, countersigned, and sealed this 27th day of January, A. D. 1885.
